UNITED STATES PATENT OFFICE.

WILLIAM McCLINTOCK, OF NEW YORK, N. Y.

FIRE-HOSE RACK.

Application filed January 29, 1921. Serial No. 440,857.

To all whom it may concern:

Be it known that I, WILLIAM McCLINTOCK, a citizen of the United States, and a resident of New York, county and State of 5 New York, have invented certain new and useful Improvements in Fire-Hose Racks, of which the following is a specification.

This invention relates to improvements 10 in fire-hose racks of the type designed for storing or holding fire-hose in such manner that one end of the hose may be attached to a water supply pipe and the opposite or nozzle end of the hose left free so that it may be grasped and the hose withdrawn 15 from the rack in condition ready for instant use.

Briefly stated the invention has been embodied in a U-shaped frame, the side members of which form shelves to or on which 20 are pivoted swinging members which extend inwardly between the shelves to form supports on which the hose may be looped. These swinging arms are so arranged that they will lie in parallel contiguous relation 25 when the hose has been withdrawn therefrom or in other words, when they are in position to allow the hose to be entered between the side members of the frame. The ends of the swinging arms are beveled 30 so as to present rounded guide surfaces to permit the hose to be readily entered between the arms of the frame. The open end of the U-frame is closed by a pair of swinging gate arms which are preferably 35 arranged to be impositively locked to the frame to prevent accidental opening of the gates after they have been closed to hose-supporting position.

Other features of novelty and construction will appear from the detailed description taken in connection with the accompanying drawings forming part of the specification in which:

Fig. 1 is a plan view showing one embodiment 45 of the invention, the swinging arms being in position to allow the hose to be entered therebetween, the dotted lines showing them in hose-supporting position.

Fig. 2 is a vertical section taken on the 50 plane of line 2—2 of Fig. 1.

Fig. 3 is a vertical section on an enlarged scale taken on the plane of line 3—3 of Fig. 1.

Fig. 4 is a view in side elevation of one 55 end of the U supporting frame showing the last or gate arm as seated in a notch in the

frame to prevent its being accidentally moved or opened.

Fig. 5 is a plan view of a fragment of the 60 frame showing the position of the swinging arms when in hose supporting position.

Fig. 6 is a side elevation of the hose rack showing the same as supporting a hose.

The rack of the present invention is 65 adapted to be pivotally supported to any suitable means, but for convenience of illustration I have shown the same as supported by clamp 10 to a pipe 11 to which one end of the hose is connected. The rack is preferably of U-form having a rather deep body 70 12 from which projects a pair of spaced lugs 13 which are adapted to straddle the horizontally extending lug on the clamp 10, a pintle 14 passing through the lugs whereby 75 the frame may be swung in a horizontal plane. Projecting from the body 12 is a pair of spaced webs 15 having inwardly projecting shelves 16 on which hose supporting mechanism is mounted. This 80 mechanism comprises a series of arms 17 swingingly supported in spaced and opposed relation on the shelves. These arms have bearing bosses 18 through which pass pivot posts 19, the latter being affixed in 85 any approved or desired manner to the shelves.

The arms 17 are tangent to the bosses 18 which latter are preferably circular in cross section to provide maximum bearing surfaces on the shelves. The arms 17 are preferably 90 extended to form stops 20 of such length that when the arms 17 are perpendicular to the webs 15 the stops will engage the vertical webs 15 and thereby prevent further inward movement of the arms. By 95 arranging the arms tangent to the bosses and hence offset laterally from their pivotal axes, the arms can be made to project further into the space between the shelves 100 than if they extended radially from the bosses. This is for the reason that the arms when swung to hose-releasing position as 105 shown in full lines in Fig. 1 are not only in parallel relation but are in contiguous relation thus permitting the free ends of the arms to approach the adjoining pivot posts more closely, it being understood that the clear distance between the mechanism of the side members of the U-frame must be such as to permit the hose to be freely entered and withdrawn. Since the arms 17 can be 110 made longer, the distance between the adja-

cent ends of the arms, when in hose supporting position, is reduced to a minimum. The pivot posts 19 are spaced apart sufficiently to allow the hose to be hung in 5 properly spaced loops (Fig. 6) and they are so disposed with respect to the vertical webs 15 that the abutments 20 will clear the adjacent bosses when the arms are in hose releasing position, as clearly shown in Fig. 1. 10 The shelves 16 need only be wide enough to provide a bearing surface for the bosses 18, the webs 15 serving to give rigidity to the shelves.

In order to permit the hose to be guided 15 between the frame without obstruction from the ends of the arms 17, the latter are beveled or rounded as at 21, these ends therefore serving as guiding means for the hose. It will be noted that these ends extend 20 beyond or overlie the edges of the shelves 16 which latter consequently do not form guides for the hose. This manner of guiding the hose between the frame is an important feature of the invention since a considerable 25 saving in material is obtained by making the shelves only of sufficient width to support the swinging arms and the frame as a whole may be made much lighter than heretofore without sacrifice of strength of 30 the same.

At the other end of the U-frame there is 35 provided a pair of gate arms 25 which are preferably of a length to provide a practically continuous support for the hose between the shelves 16. These gate arms are supported to swing about pivot posts 26 which are suitably secured to the shelves 16. These pivot posts are of a length sufficient 40 to allow the gate arms to have longitudinal movement thereon without becoming disengaged therefrom for a purpose that will presently appear. In order to provide a substantial support for these gate arms, which carry the last loop of the hose to 45 which the comparatively heavy nozzle is secured, the shelves are made somewhat wider at these points and the pivot posts 26 are spaced further apart on the frame than are the pivot posts 19.

It is desirable to arrange these gate arms 50 so that they will not be accidentally swung open. To obtain this result there is provided an impositive lock which preferably consists of a recess or groove 27 in the shelf, the arms 25 on their under sides being of 55 V shaped form as indicated at 28 whereby the arms will seat in these recesses but may readily ride up therefrom and then slide on the shelf into the position shown in 60 Figure 1.

Adjacent the groove 27 is a stop pin 30 65 against which the gate arms may abut when swung to close the open end of the frame. The pins also serve as stop means for the outer pair of swinging arms.

From the above it will be seen that I have provided a hose rack which is simple in construction and which may be manufactured at low cost. While I have described the invention with great particularity of detail I 70 desire it to be distinctly understood that I intend no limitations on the invention except as may be defined by the appended claims.

What I claim as new and desire to secure 75 by Letters Patent is:

1. In a hose rack, spaced supporting members separated at one end to permit discharge of a hose positioned therebetween and hose carrying arms pivoted in closely spaced relation on said members, said arms being relatively long to project a considerable distance across the space between the supporting members to provide long reaching supports for the loops of hose, said arms being laterally offset from their pivotal axes toward the side which is away from the discharge end of the rack when the arms stand in their projecting relation and whereby the arms will fold together in closely overlapping slightly inclined relation to permit quick and free discharge of the hose and enable easy replacement of the hose therebetween.

2. The structure of claim 1 in which the lateral offsetting of the arms is effected by constructing the arms with centrally perforated pivot bosses and by disposing the arms tangentially of such bosses.

3. The structure of claim 1 in which the arms in both their outstanding and in their folded positions project beyond the supporting members and are constructed at their overlapping ends with curved guiding surfaces to freely guide the hose entered between the supporting members.

4. In a hose rack, a supporting member and hose carrying arms pivoted in closely spaced relation on said member, said arms being relatively long to project a considerable distance beyond the supporting member and thereby provide long reaching supports for loops of hose and being offset laterally from their pivotal axes in a direction away from the discharge end of the rack, whereby said arms in the hose discharging position will fold together in closely overlapping slightly inclined relation.

5. The structure of claim 4 in which the laterally offset arms are extended beyond their pivotal axes to provide rearwardly projecting laterally offset stops and in which the supporting member has an upstanding flange for engagement by such laterally offset stops.

6. In a hose rack, a pair of spaced substantially parallel shelves widened outwardly at the discharge end of the rack, hose carrying arms pivoted on the shelves, gate arms pivoted on the widened end portions

of the shelves, said gate arms being longer than the other hose supporting arms and the pivots of said gate arms being separated a greater distance than the pivots of the other opposed hose supporting arms, said widening of the shelves thereby enabling the use

of the longer gate arms pivoted a greater distance apart and providing relatively broad supports for bracing said longer arms.

In witness whereof, I have hereunto set my hand this 28th day of January, 1921.

WILLIAM McCLINTOCK.
